UNITED STATES PATENT OFFICE

MANTHUS SATTERLEE, OF NORTH BROOKFIELD, NEW YORK.

PLOW.

SPECIFICATION forming part of Letters Patent No. 308,283, dated November 18, 1884.

Application filed June 27, 1884. (No mod.1.)

To all whom it may concern:

Be it known that I, MANTHUS SATTERLEE, a citizen of the United States, residing at North Brookfield, in the county of Madison 5 and State of New York, have invented a new and useful Plow, of which the following is a specification, reference being had to the accompanying drawings.

This invention relates to plows; and it has 10 for its object to provide an improved form of beam to which a series or gang of plows may be attached.

A further object of the invention is to provide an improved form of standard for attaching the handles to the beams, whereby the 15 handles may be moved up or down and to the right or left, as may be found desirable; and a still further object of my invention is to provide a superior plan of attaching the 20 plow-standards to the beam, whereby the plows may be moved laterally to suit the work required to be done.

With these and other objects in view, the 25 said invention consists in certain details of construction and combination of parts, as hereinafter set forth, and particularly pointed out in the claim.

In the accompanying drawings, Figure 1 is 30 a perspective view, looking at the front of the machine, of my improved gang-plow with all the parts attached in position. Fig. 2 is a rear perspective view of the same. Fig. 3 is 35 a detail perspective view of the standard, which connects the handles to the beam. Fig. 4 is a longitudinal section through one of the branches of the beam. Fig. 5 is a transverse section.

Like letters refer to corresponding parts in the several figures.

40 Referring to the drawings, A designates the plow-beam, comprising two branches CD, one longer than the other, and to the rear end of which the plows are attached in the manner hereinafter described, the branches being connected together by cross-bars B and threaded rods F with nuts G. In this manner the branches will be held together parallel with each other, and there will be no danger of the parts separating while in use.

50 H designates plows bifurcated at their upper end to form standards I², each of which have lateral extensions, J², formed at their

upper ends, said extensions being slotted at K² to receive a suitable bolt, L², provided with a nut, M², at the upper end, said bolt passing 55 through the branches of the beam and operating in the manner described, so that by loosening the nuts the bolts will allow the adjustment of the plows laterally to suit the work required to be done, when the nuts can 60 be tightened to hold the plows in that adjustment.

It will be seen that by reason of the variation in the length of the branches C D the 65 plows are arranged on one side, one being forward of the other, so that the rear plow will cover the furrow made by the front plow.

N² designates a U-shaped bracket, one arm of which is pivoted to the side of branch D of the beam A, and the other arm is slotted at 70 O² to receive a binding-screw, P², which enters the branch D, the bracket being slotted at Q² at the point of junction of the two arms, said slot Q² receiving the journal t of roller or wheel R², a nut, u, being arranged to bind 75 the journal at any point within the slot, so as to adjust the roller or wheel laterally, as desired. By reason of the pivoting of one arm of the bracket the latter can be swung on said pivot-point and held by the binding-screw P² at any point of the slotted arm, so as to adjust the wheel or roller vertically or hold it entirely off the ground.

A clevis, I, of the usual form, is detachably secured to the cross-bar B at the front end of 85 the beam, a series of holes being formed therein to receive the pivot-bolt of the clevis, which can thus be adjusted laterally as desired.

K designates the handles, of the usual form, converging toward their inner ends and connected together by a cross bolt or pin, L, one 90 of the bolts L², which connect the plow-standards I² to the beam, likewise connecting the handles thereto.

N designates the standard connecting the 95 handles to the rear end of the beam, said standard being approximately U-shaped in form and having its two arms slotted at the ends, as at O, bolts Q passing through the slots O into the handles and held by nuts n in any 100 position within the slots, so that the handles may be adjusted vertically to any desired degree. A slot, P, is formed in the standard N at the center at the junction of the two arms

thereof, a bolt, S, passing through this slot into the beam and provided with a nut to hold the handle to any position to which it may be adjusted from the right to the left. A transverse brace bar or rod, Z², connects the two arms of the standard N, and thus braces the same.

It will be seen that by means of this construction the handles may be adjusted both laterally and vertically to suit the work required to be done and the position of the plows, and may be transferred from one branch, C, of the beam to the other branch, D, as found desirable.

15 This plow is intended more especially to be used in cultivating hops, the plows being arranged in gangs for that purpose; but it will be obvious that it may be used for other purposes, as will be considered convenient. Any 20 ordinary plow may be attached to the beam, one plow being arranged slightly in rear of the other, so as to cover the furrow made by the forward plow.

Other advantages of my invention will be 25 apparent to those skilled in the art to which this invention appertains. The whiffletree is

attached to the clevis in the manner well known. The plows are adjusted laterally in relation to each other to suit the work required to be done, while the handles may also be adjusted for a similar purpose.

The plow is simple in construction and inexpensive to manufacture, and will prove of great utility and convenience for the purposes intended.

35 Having described my invention, I claim—

In a plow, the combination, with the plow-standard having the cross-slot and the plow-beam comprising two branches connected together, of the handles K, vertically pivoted at 40 their inner ends, and the handle-brace N, consisting of two arms connected together by a cross-bar, Z², the upper ends of the arms being slotted at O, and a similar slot, P, being formed at the junction of the two arms, as set forth. 45

In testimony that I claim the foregoing as my own I have hereto affixed my signature in presence of two witnesses.

MANTHUS SATTERLEE.
